LIPSTICK HOLDER

Lucille Blake, New York, N. Y.

Application November 16, 1946, Serial No. 710,349

6 Claims. (Cl. 206—56)

1

This invention relates to lipstick holders and has as its general object the provision of a lipstick holder having a holding cup or holding cup assembly arranged in such a manner as to expedite the replacement of old, consumed lipstick stubs. This object is achieved by providing a lipstick holder cup which is removably securable within the main carrier attached to the actuating mechanism of the lipstick holder. This construction allows separation of the lipstick holder cup from the lipstick holder proper for expeditious removal and replacement of the old lipstick stub, thereby eliminating the attendant difficulties encountered in lipstick holders of conventional type wherein the lipstick carrier cannot be removed without irreparable damage and loss of function to the lipstick holder.

It is another object of the invention to provide a lipstick holder for the accommodation of lipsticks of different sizes and diameters, thereby extending the use of the lipstick holder and resulting in economy for the consumer. This object is achieved by providing a lipstick holder cup of springy, resilient material which is further designed for expansion or contraction from its normal size and shape as determined by the diametrical size of the particular lipstick selected for use. This latter property of flexible accommodation may be imparted to the holder cup or holder cup assembly by means of a split or slotted construction in the resilient material thereof, by resiliently overlapping the material upon itself in a manner more fully described below or by other means.

It is a further object of the invention to provide a lipstick holder of the character indicated which can be cheaply and easily fabricated from a minimum number of parts and which will be attractive in appearance and durable and efficient in use.

The above objects as well as additional objects and advantages will readily appear in the course of the following description taken in connection with the accompanying drawing, wherein:

Fig. 1 is a view partly in section of a lipstick holder of the swivel type embodying the features of the invention and illustrating the holder cup assembly in fully extended position;

Fig. 2 is a view similar to Fig. 1 but with the holder cup assembly in retracted position, the lipstick being illustrated in dot-and-dash outline;

Fig. 3 is a view of the lipstick holder on a reduced scale partly broken away to show the carrier cup with the holder cup removed;

Fig. 4 is a perspective view showing the lipstick secured within the holder cup before insertion within the carrier cup of the holder;

Fig. 4A is a fragmentary view illustrating a lipstick of greater diameter secured within the holder cup with the holder cup distended from its normal size and shape;

Fig. 5 is an enlarged detail view clearly showing the construction of the holder cup;

Fig. 6 is an enlarged detail view of the carrier cup within which the holder cup of Fig. 5 is removably insertable;

Fig. 7 is a sectional view of the carrier cup taken along line 7—7 of Fig. 6;

Fig. 8 is a sectional view of the lipstick holder taken along line 8—8 of Fig. 1;

Fig. 9 is an elevational view of an alternative holding cup which may be employed in the lipstick holder;

Fig. 10 is a sectional view of the modified holding cup taken along line 10—10 of Fig. 9.

Referring first to Figs. 1 and 2 of the drawing, the lipstick holder 10 comprises an outer casing 11, an intermediate sleeve 12 provided with a helical groove 12a, said intermediate sleeve and said outer casing being associated in a manner to prevent relative movement therebetween, an inner guide sleeve 13 provided with a longitudinal slot 13a and terminating at its lower end in an enlarged head 14 and a lower cap fixed to the enlarged head 14 and having its shoulders in abutment against the lower extremity of outer casing 11.

The guide sleeve 13 may be rotated within the intermediate sleeve 12 by manipulation of the external cap 15 which is affixed to the enlarged head portion 14 of said guide sleeve. A lipstick carrier cup 16 is slidably mounted within the inner guide sleeve 13 and is provided with a lateral projection or lug 17 extending through the longitudinal slot 13a in said inner guide sleeve and within the helical groove 12a in the intermediate sleeve 12. It is thus seen that manipulation of the external cap 15 will serve to raise or lower lipstick carrier cup 16 as desired.

The above-described construction is typical of a well-known, conventional form of lipstick holder commonly designated as a swivel-type or rotary lipstick holder. The present invention departs now from conventional structure and embodies novel features and relationships of elements to be described herebelow.

The carrier cup 16 is preferably of spring steel or any other suitable resilient material and is formed with an annular, radially outwardly extending groove 18 intermediate its top and bottom. The carrier cup 16 is further provided with a plurality of spaced, longitudinal slots 19 extending downwardly from the top edge thereof to de-

fine separate side wall sections 16a and to permit expansion and contraction from its normal configuration for a purpose to be described below.

A lipstick holder cup 20 of spring steel or any other suitable resilient material is provided for removable insertion within the carrier cup 16. Holder cup 20 is preferably provided with a top flange 21 to limit the insertion of said cup within the carrier cup 16 and to facilitate removal therefrom. Suitably disposed between top flange 21 and the bottom of the holder cup 20 is an annular, radially outwardly extending protuberance 22 engageable in the complementary groove 18 of carrier cup 16 upon insertion of the holder cup 20 therewithin. In order to accommodate lipsticks of different diametral sizes, the holder cup 20 which, in the first instance, is constructed of springy, resilient material may be provided with a plurality of spaced longitudinal slots 23 extending downwardly from the top flange 21 and below the annular protuberance 22. This construction permits the internal diameter of holder cup 20 to be enlarged to accommodate a lipstick 25 of increased diameter, as illustrated clearly in Fig. 4A, or to be diminished to accommodate a lipstick 4 of smaller diameter 26, as illustrated in Fig. 4. It is obvious that the holder cup 20 may be adjusted to retain a large variety of lipsticks of different diametral sizes and this is a considerable advantage over known and available lipstick holders of conventional design.

When it is desired to replace a worn lipstick, the carrier cup 16 with the retained holder cup 20 is extended to the top of the lipstick holder in the customary and conventional manner whereupon the holder cup 20 may be removed by a pushing and lifting motion from its engagement within carrier cup 16. The presence of the top flange 21 greatly facilitates this latter operation. After removal of the holder cup 20 from its retained position within the carrier cup 16, the worn lipstick may be easily removed using a pin, pen knife or similar instrument which may be inserted into the lipstick through one of the longitudinal slots 23. If desired, the bottom of holder cup 20 may have an opening therein (not shown) to further expedite the operation. A fresh lipstick may now be pushed easily into the holder cup 20 simultaneously squeezing the split holder cup between the fingers to assure a firm hold on the lipstick. If desired, the holder cup 20 may have a projection or prong (not shown) struck out from the body thereof to assist in positively retaining the lipstick. The holder cup 20 with the fresh lipstick retained therein is now inserted within the carrier cup 16 in its extended position at the top of the lipstick holder and pushed downwardly until it snaps into proper position with its annular protuberance 22 engaged within the cooperating annular groove 18 in the carrier cup 16, and with the bottom of its top flange 21 in abutment against the top edge of carrier cup 16. The carrier cup 16 with its retained holder cup 20 and lipstick may then be retracted within the holder in the customary manner until it is desired to apply the lipstick.

Figs. 9 and 10 illustrate another form of holder cup embodying the features of the invention. In this embodiment the holder cup 30 is formed of resilient spring steel or other suitable material shaped to form a cup of variable diameter having overlapping portions 31 and 32. A top flange 33 is provided to serve the functions described in connection with the top flange 21 of holder cup 20. Similarly to holder cup 20, holder cup 30 is pro-

vided with an annular, radially outwardly extending protuberance 34 intermediate the top flange 33 and the bottom of the cup 30 which protuberance cooperates with the annular groove 18 of carrier cup 16 in a manner similar to that described above in connection with the holder cup 20 of split or slotted construction. The inner diameter of holder cup 30 may be increased by separating overlapping portions 31 and 32 to accommodate lipsticks of increased diameter and may be diminished by compressing or further overlapping portions 31 and 32 to accommodate lipsticks of smaller diameter. Insertion and removal of holder cup 30 from carrier cup 16 is accomplished in a similar manner to that described above in connection with holder cup 20.

While the drawings illustrate the invention as being embodied in a lipstick holder of the rotary or swivel type, it is obvious that the invention is adaptable to other types of holders such as the common push type of holder. Also, the drawings illustrate carrier cup 16 and holder cups 20 and 30 of being of circular cross-section to accommodate and retain cylindrical lipsticks. It is observed that the carrier cup and holder cup could be modified to have square, triangular or other cross-sections depending upon the cross-section of the particular lipstick to be retained within the holder.

Since certain additional modifications may be made in the lipstick holder of my invention without departing from the scope thereof, it is intended that all matter contained in the foregoing description and shown in the accompanying drawing be interpreted merely as illustrative and not in a limiting sense.

I claim:

1. In a lipstick holder having a closed end and an open end, a carrier cup mounted for longitudinal movement within said holder, actuating means for propelling and repelling said carrier cup between the open end and the closed end of said holder, said actuating means being operable from the outside of said lipstick holder and being associated with a stop member positioned to stop the propulsion of said carrier cup when said carrier cup reaches the open end of said lipstick holder and before said carrier cup is ejected from said open end, said carrier cup having an annular, radially outwardly extending groove intermediate the top and bottom thereof, a plurality of spaced longitudinal slots extending downwardly from the top edge thereof, and a lipstick holder cup removably insertable within said carrier cup, said holder cup having an annular, radially outwardly extending protuberance intermediate the top and bottom thereof, said annular protuberance cooperating with said annular groove in said carrier cup for removably securing said holder cup therewithin, said holder cup having a resilient side wall which is split longitudinally to enable the diameter of said side wall to be varied, whereby to accommodate lipsticks of varying diametral sizes.

2. A lipstick holder according to claim 1 in which the lipstick holder cup is provided with an annular, radially outwardly extending flange along its upper peripheral edges, said flange being positioned outside the open end of said lipstick holder when said carrier cup is propelled to the limit permitted by said stop member, said flange serving as a finger catch whereby said cup may readily be removed from the carrier cup.

3. In a lipstick holder having a sleeve which has a helical groove, a carrier cup mounted for

longitudinal movement within said sleeve, means operable from the outside of said lipstick holder for turning said carrier cup relative to said sleeve, said carrier cup having a side wall which has an annular, radially outwardly extending groove intermediate the top and bottom thereof, a plurality of spaced, longitudinal slots extending downwardly from the top edge thereof, and a struck out laterally projecting tongue intermediate the top and bottom thereof, said tongue extending into the helical groove of said sleeve and being adapted to move said carrier cup longitudinally when said carrier cup is turned relative to said sleeve, and a lipstick holder cup removably insertable within said carrier cup, said holder cup having an annular radially outwardly extending protuberance intermediate the top and bottom thereof, said annular protuberance cooperating with said annular groove in said carrier cup for removably securing said holder cup therewithin, said holder cup having a resilient side wall which is split longitudinally to enable the diameter of said side wall to be varied, whereby to accommodate lipsticks of varying diametral sizes.

4. In a lipstick holder having a closed end and an open end, a carrier cup mounted for longitudinal movement within said holder, actuating means for propelling and repelling said carrier cup between the open end and the closed end of said lipstick holder, said actuating means being operable from the outside of said lipstick holder and being associated with a stop member positioned to stop the propulsion of said carrier cup when said carrier cup reaches the open end of said lipstick holder, said carrier cup having an annular, radially outwardly extending groove intermediate the top and bottom thereof and having a plurality of spaced longitudinal slots extending downwardly from the top edge thereof and a resilient lipstick holder cup removably insertable within said carrier cup, said holder cup having an annular, radially outwardly extending protuberance intermediate the top and bottom thereof, said annular protuberance cooperating with said annular groove in said carrier cup for removably securing said holder cup therewithin, said holder cup having a plurality of longitudinal slots extending downwardly from the top edge thereof and below said annular protuberance whereby to accommodate lipsticks of varying diametral sizes. 50

5. A lipstick holder according to claim 4 in which the lipstick holder cup is provided with an annular, radially outwardly extending flange along its upper peripheral edge, said flange being positioned outside the open end of said lipstick holder when said carrier cup is propelled to the limit permitted by said stop member, said flange serving as a finger catch whereby said cup may readily be removed from the carrier cup.
10. 6. In a lipstick holder having a sleeve which has a helical groove, a carrier cup mounted for longitudinal movement within said sleeve, means operable from the outside of said lipstick holder for turning said carrier cup relative to said sleeve, said carrier cup having a side wall which has an annular, radially outwardly extending groove intermediate the top and bottom thereof and a plurality of spaced, longitudinal slots extending downwardly from the top edge thereof, and a struck-out, laterally-projecting tongue intermediate the top and bottom thereof, said tongue extending into the helical groove of said sleeve and being adapted to move said carrier cup longitudinally when said carrier cup is turned relative to said sleeve, and a resilient lipstick holder cup removably insertable within said carrier cup, said holder cup having an annular radially outwardly extending protuberance intermediate the top and bottom thereof, said annular protuberance cooperating with said annular groove in said carrier cup for removably securing said holder cup therewithin, said holder cup having a plurality of longitudinal slots extending downwardly from the top edge thereof and below said annular protuberance whereby to accommodate lipsticks of varying diametral sizes.
